United States Patent Office

Des. 187,730
Patented Apr. 26, 1960

187,730

COMMERCIAL BUILDING

Richard M. Barancik, Chicago, Ill., assignor to The Golden Hamburger Drive-In Corporation, Chicago, Ill.

Application June 11, 1958, Serial No. 51,302

Term of patent 14 years

(Cl. D13—1)

FIG. 5

FIG. 4

Fig. 1 is a top perspective view on a reduced scale of a commercial building embodying my new design;

Fig. 2 is a side elevational view thereof;

Fig. 3 is a similar view of the opposite side;

Fig. 4 is a front elevational view thereof; and

Fig. 5 is a rear elevational view thereof.

I claim:

The ornamental design for a commercial building, substantially as shown.
